CHILD'S COASTER VEHICLE

John C. Rumsey, Lawrence, Kans.

Application May 5, 1955, Serial No. 35,846

Term of patent 7 years

(Cl. D34—15)

Fig. 3.

Fig. 1 is a perspective view of a child's coaster vehicle, showing my new design;

Fig. 2 is an end elevational view thereof; and

Fig. 3 is a top plan view thereof.

I claim:

The ornamental design for a child's coaster vehicle, substantially as shown.
